UNITED STATES PATENT OFFICE.

WILLIAM C. DALBEY, OF DUQUOIN, ILLINOIS, ASSIGNOR TO THE CLEVELAND DENTAL MANUFACTURING COMPANY, OF CLEVELAND, OHIO, A CORPORATION OF OHIO.

ROOT-BEVELING DEVICE.

1,157,681.

Specification of Letters Patent.

Patented Oct. 26, 1915.

Application filed January 18, 1913. Serial No. 742,809.

To all whom it may concern:

Be it known that I, WILLIAM C. DALBEY, a citizen of the United States, residing at DuQuoin, in the county of Perry and State of Illinois, have invented a certain new and useful Improvement in Root-Beveling Devices, of which the following is a full, clear, and exact description.

This invention relates to a root beveling device which is adapted to be attached to the hand piece of an ordinary dental engine for the purpose of beveling the margin of a root preparatory to applying thereto a so-called swaged cap or banded crown.

The object of the invention is the provision of a device by which a root may be beveled easily, quickly and uniformly entirely about its margin without mutilating the gum.

The invention may be briefly summarized as consisting in certain novel details of construction and combinations and arrangements of parts which will be described in the specifications and set forth in the appended claims.

In the drawings wherein I have shown an embodiment of my invention which answers the requirements with high efficiency, Figure 1 is an elevation of the device attached to the hand piece of a dental engine showing the manner in which it is used in beveling the margin of a root; Fig. 2 is a sectional view substantially along the line 2-2 of Fig. 1; Fig. 3 is a detached view of the pivotal pin about the axis of which the bar or beveling tool is revolved.

Referring now to the drawings, it will be seen that my invention is in the nature of an attachment to an ordinary hand piece 10 of a dental engine. The attachment includes a sleeve-like member 11 which is adapted to be slipped onto the hand piece and to be held from rotation thereon by any suitable locking means which in this case includes a pin 10^a of the hand piece and a slot 11^a of the sleeve, which slot receives the pin, as shown in Fig. 2. Attached to the sleeve, or to a strip or metal piece alongside the sleeve, preferably by one or more screws 50 12, is a rather stiff flat spring 13 which extends upwardly alongside of the sleeve, and beyond the end thereof, as shown. Secured in any suitable manner to the upper or free end of the spring 13 is a device 14 which may be termed a head. This head is pro-

vided with a lateral projection 14^a having an elongated slot 14^b, through which is adapted to project freely the shank of a bur 15 for beveling the margin of the root. This bur will be rotated through the medium of the flexible shaft of a dental engine in the usual manner, and its shank will have any suitable form of driving connection with the driving or rotating part in the hand piece. As this forms no part of the present invention, I have not illustrated details of the driving connection, or any of the details of the hand piece. The head 14 additionally has an opening or passageway which extends substantially at right angles to the projection 14^a and in this opening is adapted to be secured a pivoting pin 16. This pin 16 has at its upper end a reduced portion 16^a which is adapted to extend into the canal of the root which is shown at 17, and below the reduced portion 16^a, the pin 16 is provided with a shoulder 16^b which when the device is in use, is adapted to bear against the end of the root as shown in Fig. 1. The pin 16 is preferably secured on the head 14 by means of a set screw 18, which enables the pin to be adjusted in its position in the head, either lengthwise or circumferentially. Preferably, the lower end of the pin 16 is beveled as shown at 16^c, the beveled end extending downward in proximity to the upper conical or tapered end of the hand piece 10.

In the use of the device so far described, the parts are assembled on the hand piece as shown, with the shank of the bur extending freely through the slot 14^b. Thence to bevel the margin or edge of the root, the reduced end of the pin is inserted in the canal of the root, and thence the beveling bur is rotated in the usual manner by the power of the dental engine, and at the same time the hand piece is turned about the pin as an axis. The spring 13 which connects the pin with the sleeve, being yieldable or elastic, presses the bur against the margin of the tooth and allows it to follow or conform to the irregularities of the margin of the tooth, the bur then moving inwardly toward or outwardly away from the pivoting pin, but at all times being held against the margin of the root. When the bur is thus revolved a few times about the root, the margin of the latter will be uniformly beveled throughout its entire periphery or perimeter.

The relative inward and outward movement between the bur and the pin 16 will depend to a certain extent upon the length of the slot 14^b, back and forth along which the bur is adapted to travel during the beveling operation. I prefer, however, to utilize the pin 16 to limit the inward movement of the bur,—hence, the function of the beveled lower end 16^c of the pin 16. In the preferred use of the device, the movement of the bur toward the pin 16^c is limited by the engagement of the lower end of the pin with the tapered upper end of the hand piece. By turning the pin 16 so that different points of the beveled end 16^c may contact with the end of the hand piece, the distance that the beveling bur can be held from the pin can be accurately and very nicely adjusted. The practical advantages of this feature lie in the fact that I am thus enabled to vary the width or amount of the bevel and also to provide a limiting stop against the inward movement of the bur toward the pin so as to prevent the bur moving inward sufficiently to engage the enlargement or shoulder 16^b. I prefer also to provide means for adjusting the effective tension of the spring 13 so as to vary the pressure of the bur against the margin of the tooth. This is accomplished in a simple and effective manner by means of a short screw 19 which is carried by the sleeve and extends loosely through the spring 13 a suitable distance from its lower end. As the screw is moved inward, the spring is made stiffer, for its effective length is then decreased, and as the screw is moved outward, the stiffness is decreased.

It will be obvious that the attachment above described can be quickly applied to the hand piece of a dental engine, and that in a very short space of time the root can be beveled to just exactly the extent required, and with uniformity at all points, regardless of the shape of the margin of the root, or its regularity or irregularity. Furthermore, the beveling can be accomplished without mutilating the gum and without material discomfort to the patient.

I do not desire to be confined to the exact details shown, but aim in my claims to cover all modifications which do not involve a departure from the spirit and scope of my invention.

Having thus described my invention, what I claim is:

1. The combination with the hand-piece of a dental engine having a cutting tool, of a root beveling attachment comprising a pivot adapted to be inserted in the canal of

a root, said pivot extending alongside the cutting tool and being detachably connected to and yieldingly supported from the hand-piece.

2. The combination with the hand-piece of a dental engine having a cutting tool, of a root beveling attachment comprising a device detachably connected to the hand-piece, a pivot member adapted to be inserted in the canal of a root, and a spring carrying said pivot member and attached to said device.

3. A root beveling attachment for the hand piece of a dental engine comprising a device adapted to be attached to the hand piece, a pivot adapted to be inserted in the canal of a root and having a yieldable support connected to said device, said support having a laterally projecting member provided with a slot adapted to accommodate the shank of a beveling tool.

4. A root beveling attachment for the hand piece of a dental engine comprising a sleeve adapted to be placed on the hand piece, a leaf spring connected to said sleeve and extending alongside and beyond the same, said spring having at its outer free end a member carrying a pivot pin adapted to be inserted in the canal of a root, said member having a lateral projecting portion provided with an elongated slot adapted to receive the shank of a beveling tool.

5. A root beveling attachment for the hand piece of a dental engine comprising a device adapted to be attached to the hand piece, a yieldable support extending alongside said device and connected at one end thereto, a pivot pin carried at the opposite end of said support and adjustable relative thereto both circumferentially and longitudinally, said pin having at its outer end a portion adapted to be inserted in the canal of the root, and its inner end being beveled for the purpose set forth.

6. The combination with a root grinder having a hand piece and a grinding tool projecting beyond the end thereof, a pivot extending alongside the grinding member and adapted to be inserted in the canal of a root, a member detachably connected to the hand piece, and means connecting said pivot to said member, said means permitting relative lateral movement between the pivot and the grinding tool.

In testimony whereof, I hereunto affix my signature in the presence of two witnesses.

WILLIAM C. DALBEY.
